Des. 236,888
Patented Sept. 23, 1975

236,888

TIRE

Henri Verdier, Beauregard-L'Eveque, France, assignor to
Compagnie Generale des Etablissements Michelin,
Clermont-Ferrand, France

Filed Dec. 17, 1973, Ser. No. 425,234

Claims priority, application France June 18, 1973

Term of patent 14 years

Int. Cl. D12—15

U.S. Cl. D12—147

FIG. 1

FIG. 3

FIG. 2

FIG. 1 is a perspective view of a tire showing my new design, it being understood that the tread pattern is repeated throughout the circumference of the tire as shown schematically by solid lines;

FIG. 2 is an enlarged fragmentary developed plan view thereof; and

FIG. 3 is a cross sectional view thereof taken on the line 3—3 of FIG. 2.

I claim:

The ornamental design for a tire, as shown and described.
